(57) **CLAIM**

I claim the ornamental design for a railing and sunshade support for a pool, as shown and described.

DESCRIPTION

FIG. 1 is a perspective view of the subject of the design invention shown in the environment of a swimming pool and a sunshade umbrella, all but the invention shown in phantom broken lines are for illustrative purposes only and form no part of the claimed design;

FIG. 2 is a left side elevation thereof, the right side a mirror image thereof;

FIG. 3 is a rear elevation view thereof;

FIG. 4 is a front elevation view thereof;

FIG. 5 is a bottom plan view thereof; and,

FIG. 6 is a top plan view thereof.
